UNITED STATES PATENT OFFICE.

MEINER C. MORK, OF HECTOR, MINNESOTA.

CONNECTING GUIDE REIN OR STRAP.

1,094,462.

Specification of Letters Patent. Patented Apr. 28, 1914.

Application filed October 20, 1913. Serial No. 796,283.

To all whom it may concern:

Be it known that I, MEINER C. MORK, a citizen of the United States, residing at Hector, in the county of Renville and State 5 of Minnesota, have invented a new and useful Connecting Guide Rein or Strap; and I do hereby declare the following to be a full, clear, and exact description of the invention, such as will enable others skilled 10 in the art to which it appertains to make and use the same.

This invention relates to a new and useful improved connecting guide rein or strap.

An object of the invention is the provision 15 of a device of this design for connecting a plurality of horses, say for instance four or more, so as to easily guide them when hitched to a vehicle.

The foregoing device is so constructed 20 that when a pulling action is exerted upon one or the other of the outer horses, in order to guide them to the right or left, the pulling action is transferred to the opposite outer horse, without materially transferring 25 the pulling action to the intermediate horses. In other words, the pull for guiding the outer horses in one direction or the other is direct, from one outer horse to the other. Furthermore, a portion of the connecting 30 guide reins or straps may be used as a hitching device, as shown in one of the views of the drawing.

In practical fields the details of construction may necessitate alterations, to which 35 the patentee is entitled, provided the alterations fall within the scope of what is claimed.

The invention comprises further features and combination of parts, as hereinafter set forth, shown in the drawings and claimed.

40 In the drawings: Figure 1 is a view in plan showing the construction and arrangement of the connecting guide rein or strap connected to four bits. Fig. 2 is a sectional view through a portion of said connection. 45 Fig. 3 is a view of the bit 2 as applied to a horse's mouth.

Referring more particularly to the drawings, 1, 2, 3 and 4 designate four bits. Connected to the ring 5 of the bit 1 is a snap 50 hook 6, to which the loop 7 of the strap 8 is connected, there being a buckle 9 and the slides 10, for holding the loop as shown in Fig. 1. This strap at the opposite end is

likewise constructed and connected to the ring 11 of the bit 4. However, the strap 8 intermediate the bits 1 and 4 is constructed to form loops 12 and 13, and 14 and 15, which connect to the snap hook 16 and 17, and 18 and 19, which in turn connect to the rings 20 and 21 of the bits 2 and 3. The 60 loops 12 and 13, and 14 and 15 are held in their loop arrangement, by means of the buckles 22, 23, 24 and 25 and the slide 26. Connected to the rings 28 and 29 of the bits 1 and 4 are the usual guide or check reins 65 30 and 31. When a pulling action is imparted on the reins 30, it is transmitted directly to the bit 4, without affecting or pulling upon the bit 2 and 3, and this is on account of the arrangement and provision of 70 the parts 32 and 33 of the strap 8, and it will be seen that the pull is direct from the part 34 to the part 35, which pull is transmitted by the part 32, without affecting the bit 2 in any manner, with the exception that 75 the loops are pressed against the opposite sides of the animal's lower jaw, so as to hold him firm. The buckles, 22, 23, 24 and 25 are constructed with lugs 36 to prevent the loop from displacement relative to the 80 buckle. When a pulling action is imparted upon the guide rein 31, it is transmitted directly from the bit 4 to the bit 1.

The invention having been set forth, what 85 is claimed as new and useful is:—

In improvements in a guiding connection, the combination of the single strap arranged for connecting four or more animals abreast, each end of said strap having connections to each outer animal, the intermediate portion 90 of the strap having formed therein pairs of loops having snap hooks for connection to the bits of the intermediate animals, means for holding the loops so constructed, and a connector between the loops of each pair, 95 thereby constituting means to permit the guiding pull to be transmitted directly from one outer animal to the opposite outer animal.

In testimony whereof I have signed my 100 name to this specification in the presence of two subscribing witnesses.

MEINER C. MORK.
